UNITED STATES PATENT OFFICE

GEORGE EDWARD CONDLIFFE, OF GERRADS CROSS, ENGLAND, ASSIGNOR TO VICTOP
TALKING MACHINE COMPANY, A CORPORATION OF NEW JERSEY

INDICATING CONTROL MEANS FOR VARIABLE ELECTRICAL COMPONENTS

Application filed January 23, 1931, Serial No. 510,836, and in Great Britain January 17, 1930.

The present invention relates to indicating control means for variable electrical circuit components such as tuning control devices for radio receiving apparatus and the like.

In apparatus of the above character there usually exists a certain arrangement of the variable component or tuning device and of the means for indicating the amount of variation given to the tuning device, which arrangement is the most effective for ensuring ease of control, another arrangement which provides the greatest efficiency of operation, and still another arrangement which is an improvement from the point of view of appearance.

While it is desirable that the variable component and the indicating means should be arranged so as to ensure that all these advantages may be obtained, inherent mechanical limitations often interfere therewith, and at best heretofore have often entailed the employment of complicated mechanical linkages between the variable component or tuning device and the indicating means therefor.

Among other things it is desirable to be able to provide a predetermined ratio between the movement of the indicating means and the movement of the variable component, for the reason that direct indication of the movement or position of adjustment of the component is usually not an accurate indication of its adjusted value or the operating condition in the apparatus effected by the position of adjustment to which it is moved, such as the tuning adjustment of radio apparatus controlled by the variable component. Accurate compensating or corrective control of the ratio between the component or apparatus controlled and the indicating means therefor, is difficult to provide by simple and easily operable linkages of a mechanical nature between the component and the indicating means.

Accordingly it is an object of the present invention to provide an improved indicating and control means which includes a linkage between the variable component and the indicating means, of a type adapted to

provide the above advantages without introducing accompanying difficulties heretofore experienced.

In accordance with the present invention there is provided in an indicating control means for a variable electrical component, means whereby the direction of a beam of light bearing an indicating image is varied in accordance with variations produced in the value of a variable electrical component such as the tuning component of a radio receiver, to provide a compensated and accurate indication of the adjustment of said component or of the condition of operation of the apparatus controlled by variations of said component.

The invention will be described, by way of example, and will be better understood with reference to the accompanying drawings, which show the invention as applied to the tuning control shaft of radio receiving apparatus, and its scope will be pointed out in the appended claims.

In the drawing, Fig. 1 is a plan view, partly in section, of an indicating control means embodying the invention; Fig. 2 is a view in elevation, also partly in section, of the indicating control means of Fig. 1, on the same scale; and Fig. 3 is a view in perspective, on an enlarged scale, of a detail.

Referring to the drawings, 1 is a variable electrical circuit component which, for example, may be a condenser or other tuning control means for a radio receiver, provided with and controlled by a rotary control shaft 2. Rotation of the shaft produces a corresponding rotation of a cam 3 which is mounted on the shaft coaxially therewith. A lever 4 co-operates with the cam and is held in engagement therewith by a suitable spring 5.

The lever 4 carries a mirror 6 which is illuminated by means of a lamp 7 having a hood or cover 9 provided with a light projecting orifice or opening 10 through which it projects a ray or beam of light 11 onto the mirror. The mirror bears an indicator in the form of an indicating mark 11 (Fig. 3) which is projected and moves between, and in the direction indicated by, lines 12-13

onto an indicating scale 8 of suitable translucent material.

Rotation of the control shaft 2 in tuning or operating the variable component 1 produces a corresponding deflection of the indicating mark 11 on the scale between lines 12-13 and causes the image of the mark or indicator to sweep across the scale. Since the scale is translucent, the indicator mark appears to move and lie in the scale.

The position of the scale can be chosen to the best advantage, the indicating beam being reflected thereon by a suitable disposition of the mirror. In the present example, 15 the scale is mounted in a suitable support or panel 14, preferably of opaque material, carried by a common base 15 of the apparatus along with a bracket 16 for the lamp and a support 17 for the lever. The lever 20 turns on a fixed pivot 18 carried by the support 17.

It will be noted that the light source 7 and the scale 8 lie at different levels or in different planes in Fig. 2 with respect to 25 the mirror or image reflecting device 6 or a plane normal to the latter.

It will further be noted that the light source is shielded from the scale and that the latter is thus illuminated only by the 30 indicating beam from the mirror in which beam the image of the indicator lies. The single light source, however, serves thus to illuminate the scale and provide the indication.

35 It is relatively easy to provide any desired value in the ratio of the movement of the beam of light to the movement of the operating knob, as this depends upon the dimensions of the lever or the design of the cam surface. Thus, any desired scale length can be used, and by providing a cam having the desired shape, any desired relationship between the value of the component 1 or tuning of the apparatus and the scale deflection 40 may be employed. For example it will be seen that should the scale indication desired at the scale 8 not agree with the position of the variable component 1 to indicate its value or the condition of the apparatus 45 corresponding thereto, the shape of the cam may be made to correct therefor and to hold the lever for any position of adjustment of the component 1 in such position that the image of the indicator will be projected onto the scale at the desired or correct point.

The simplified tuning control and indicating means provided is thus particularly adapted for use with radio apparatus requiring accurate indication and control of the tuning components and because of its simple construction is adapted to easily be applied thereto.

It is obvious that the embodiment shown 60 and described by way of example, may be

modified to suit different operating conditions and the physical arrangement of the apparatus employed. The simple cam controlled mirror and distant scale connected by a beam of light including an indicating image provides an accurate indication of the value of the variable component or the condition of the apparatus controlled thereby. It will be noted that this arrangement thus provides simultaneous indication and 75 illumination from the same light source.

I claim as my invention:

1. In combination, a variable electrical circuit component having an operating control shaft, a cam arranged to be moved by 80 said shaft, a scale, an indicator for the scale, and means actuated by said cam and including a movable mirror, for projecting an image of said indicator upon said scale.

2. In a radio apparatus, the combination 85 with a variable circuit component having a control shaft, of means for indicating a characteristic of the apparatus responsive to variations of said circuit component, said means including a movable mirror, an indicator carried by the mirror, a cam carried by the shaft and arranged to move said mirror in response to movement of said shaft, a light source for projecting a beam 90 of light upon the mirror and indicator, and a scale arranged in spaced relation to the mirror to intercept the projected beam of light and the image of said indicator from 95 said mirror.

3. In a radio apparatus, the combination 100 with a variable circuit component having a control shaft, of means for indicating a characteristic of the apparatus responsive to variations of said circuit component, said means including a movable mirror, an indicator carried by the mirror, a cam carried by the shaft and arranged to move the mirror in response to movement of said shaft, a light source for projecting a beam 105 of light upon the mirror and indicator, and a scale arranged in spaced relation to the mirror to intercept the projected beam of light and the image of said indicator from 110 said mirror, said scale and light source being arranged to lie in different planes with respect to each other and a plane normal to 115 the mirror.

4. In combination, a variable electrical circuit component having an operating shaft, a movable mirror, an indicator carried by the mirror, means for moving said mirror in response to movement of said shaft in accordance with variations in the electrical circuit value of said component, a scale arranged in spaced relation to said mirror to receive therefrom a beam of light and an image of said indicator, and a light source arranged to project said beam of light upon said mirror thereby indirectly to 120 125 130

luminate said scale and to provide said image of said indicator.

5. In a radio apparatus, the combination with a variable electrical circuit component having a control shaft, of means adapted to provide a beam of light, means responsive to movement of said control shaft for altering the direction of said beam of light in accordance with variations produced in the 10 electrical circuit value of said electrical component, said means including a movable mirror, an indicator on said mirror whereby said beam of light includes an image of said indicator, a translucent scale arranged 15 to intercept said beam of light and image of said indicator, and a cam mounted on said control shaft and having an operating surface connected with said mirror to move it.
- 20 6. The combination with a variable electrical circuit component, of an indicating control means therefor, including a control shaft, an indicating scale, a source of light, a mirror arranged to project a beam of light 25 from said source onto said scale, said mirror being provided with an indicating mark whereby the image of said mark appears on said scale when said mirror is illuminated by the light source, and a cam connected 30 with said control shaft and arranged to move said mirror in response to movement of the control shaft, said cam being shaped to cause said mirror to move in a predetermined manner.
- 35 In testimony whereof I have hereunto subscribed my name this sixth day of January, 1931.

GEORGE EDWARD CONDLIFFE.
